SIGURD H. HELLAND, OF WHITINSVILLE, MASSACHUSETTS, ASSIGNOR TO WHITIN MANUFACTURE WORKS, OF WHITINSVILLE, MASSACHUSETTS.

DRAWING-ROLL TRAVERSING MOTION FOR WOOL-SPINNING MACHINES.

Application filed June 15, 1928. Serial No. 285,598.

My invention has reference to an improvement in spinning machines and more particularly to an improvement in wool spinning machines.

In the usual construction of cotton spinning machines the upper drawing rolls are covered with leather. When no traverse motion is used to move the yarn back and forth between the rolls, the yarn coming straight between the rolls, will wear a groove in the leather covered rolls and thus ruin the utility of these rolls. This detrimental feature has been overcome by the use of a mechanism which traverses the yarn back and forth between the drawing rolls. This traversing mechanism is used in the form of a spinning machine known as a cotton spinning frame, but is useless in a wool spinning machine, owing to the difference in the construction of these machines.

The object of my invention is to improve the construction of a wool spinning machine, whereby the yarn is drawn straight through the drawing rolls, while the drawing rolls, by the use of my improved traversing motion, are given a traversing or an endwise reciprocating motion simultaneously with their revolving motion.

A further object of my invention is to improve the construction of such a drawing roll traversing motion or mechanism whereby the traversing or endwise motion of the drawing rolls is extremely slow compared with the revolving speed of the drawing rolls.

My invention consists in the peculiar and novel construction of a mechanism for giving a traversing or an endwise motion to the drawing rolls of a wool spinning machine, said traversing mechanism having details of construction, as will be more fully set forth hereinafter and claimed.

Figure 1 is a vertical sectional view through my improved drawing roll traversing motion for wool spinning machines and showing the adjacent portions of the machine partly in section.

Figure 2 is a vertical transverse sectional view through the drawing roll traversing motion and parts of the machine, taken on line 2, 2 of Figure 1 and looking in the direction of the arrow A.

Figure 3 is an enlarged detail vertical front

view of that part of the drawing roll traversing motion, with the casing broken away.

Figure 4 is an enlarged detail vertical sectional view taken on line 4, 4 of Figure 3, and

Figure 5 is an enlarged detail end view showing the means for holding the rear leather covered drawing rolls against the front drawing rolls, and taken on line 5, 5 of Figure 1, looking in the direction of the arrow E.

In the drawings B indicates adjacent portions of a wool spinning machine, C my improved drawing roll traversing motion and D the yarn.

The machine B has the usual frame members 1, 2, 3 and 4. Twister heads 5, 5, 5 are supported in the machine in the usual way and they have the usual whorls 6, 6, 6 which revolve the twister heads by bands F, F shown in Figure 2, from the usual driving drum, not shown. The front fluted drawing rolls 7, 7, 7 are on a shaft 8 fixed to or forming a part of a driven shaft 9, which has a reciprocating motion through and a revolving motion by a bevel gear 10, rotatably supported in a bearing in the frame member 1. This bevel gear 10 meshes with a bevel gear 11 on a shaft 12 connected to the driving mechanism, not shown, of the machine, as shown in Figure 1. The back leather covered drawing rolls 13, 13, have trunnions 14, 14 resting on flat ends of an arm 15 secured to a rod 16, as shown in Figure 5, which in turn is fixed to an extension on the closed casing 21, as shown in Figure 2. A bell crank lever 17 is pivotally supported on a frame member of the machine and has a vertical arm 18, the lower end of which bears against the trunnions 14, 14, of the back rolls 13, 13, as shown in Figure 5 and a horizontal arm 19 on which is an adjustable weight 20, as shown in Figure 2. This weighted bell-crank lever 17, forces the back drawing rolls 13, 13, against the front drawing rolls 7, 7, thereby giving the required bite of the rolls on the yarn D, which now comes straight downwards through the twister heads and drawing rolls.

My improved drawing roll traversing motion C consists of a closed casing 21 supported on the driven shaft 9 by ball bearings 22, 22 and end members 23, 23, fixed to the

driven shaft 9 as shown in Figure 1, whereby the driven shaft 9 extends through and revolves in the casing 21 and the casing 21 has a reciprocating motion with the driven shaft 9. The closed casing 21 has a front outside bearing 24 and a rear outside bearing 25. Fixed to the driven shaft 9 is a worm 26 meshing with a worm gear 27 having a cylindrical hub 28 rotatably supported on a fixed cylindrical gear hub 29, which in turn is supported on a shaft 30, rotatably supported at each end in the front and rear outside bearings 24 and 25. A gear 31 having nineteen teeth is formed integral with the fixed gear hub 29 and a gear 32 having twenty teeth is fixed to the shaft 30. A stud 33 is fixed to the worm gear 27 and rotatably supports a pinion 34 which straddles and meshes with both of the gears 31 and 32, as shown in Figures 2 and 4. Fixed to each end of the shaft 30 is a crank 35 having a crank pin 36 pivotally connected to one end of an arm 37, the other end of the arm 37 being pivotally connected to a bracket 38, which in turn is fastened to the frame member 1, as shown in Figures 1, 2 and 4.

In the operation of my improved drawing roll traversing motion, the yarn D is drawn straight down through the twister head 5 and between the driven front drawing roll 7 and the back drawing roll 13, which is pressed against the front roll by the weighted bell-crank lever 17, and is revolved through friction with the front roll 7. Revolving of the driven shaft 9 revolves the front drawing rolls 7, 7, the worm 26, worm gear 27, pinion 34 and gear 32, thereby revolving the shaft 30 part of a revolution, equal to one tooth of the gear 32, or one twentieth part of a revolution and through the cranks 35, 35, crank pins 36, 36 and arms 37, 37, a traversing or an endwise reciprocating motion, is given to the front and back drawing rolls and to the closed casing 21 and the mechanism in the casing, equal to the throw of the crank pins 36, 36.

By the new and novel construction of my improved traversing motion for wool spinning machines, the required slow endwise reciprocating motion is given to the drawing rolls while the yarn is drawn straight down between the rolls, thereby eliminating undue wear by the yarn, on the rolls.

It is evident that the ratio of the gearing and the throw of the crank pins could be materially modified and other details of construction could be changed within the scope of the appended claims.

Having thus described my invention I claim as new:

60 1. In a spinning machine having the usual frame, driving mechanism and drawing rolls, a driven shaft operatively connected with the driving mechanism and with the drawing rolls, to revolve the drawing rolls, a drawing roll traversing motion suspended from the

driven shaft and operatively connected with the driven shaft and means for operatively connecting the drawing roll traversing motion with a relatively fixed part of the machine, whereby the drawing rolls are simultaneously given a revolving and a traversing motion, for the purpose as described. 70

2. In a spinning machine having the usual frame, driving mechanism and drawing rolls, said drawing rolls being on a driven shaft 75 operatively connected with the driving mechanism, a drawing roll traversing motion suspended from the driven shaft of the drawing rolls and operatively connected with the driven shaft and means for operatively connecting the drawing roll traversing motion with a relatively fixed part of the machine, whereby the drawing rolls are simultaneously given a revolving and an endwise reciprocating motion, for the purpose as described. 80

3. In a spinning machine having the usual frame, driving mechanism, a driven shaft and drawing rolls on the driven shaft, said driven shaft being operatively connected with the 90 driving mechanism, a drawing roll traversing mechanism suspended from the driven shaft and operatively connected with the driven shaft and connecting members operatively connected with the drawing roll traversing 95 mechanism and with a fixed part of the machine, for the purpose as described.

4. In a spinning machine having the usual frame, driving mechanism, a driven shaft having drawing rolls and operatively connected with the driving mechanism, a casing suspended from the driven shaft and operatively connected with the driven shaft, a drawing roll traversing mechanism in the casing and operatively connected with the 100 driven shaft, and arms operatively connecting the drawing roll traversing mechanism with a fixed part of the machine, for the purpose as described. 105

5. In a spinning machine having the usual 110 frame, driving mechanism, a driven shaft having drawing rolls and operatively connected with the driving mechanism, a closed casing in which is a drawing roll traversing mechanism said casing being suspended from the driven shaft and operatively connected with the driven shaft and arms pivotally secured to the drawing roll traversing mechanism and to a fixed part of the machine, for the purpose as described. 115

6. The combination with a spinning machine having a frame, a driving mechanism, a driven shaft having drawing rolls and operatively connected with the driving mechanism, of a closed casing suspended from the 125 driven shaft and operatively connected with the driven shaft, a drawing roll traversing mechanism in the casing and operatively connected with the driven shaft and means operatively connecting the drawing roll trav- 130

ersing mechanism with a part of the machine frame, for the purpose as described.

7. The combination with a spinning machine having a frame, a driving mechanism, a driven shaft having drawing rolls and operatively connected with the driving mechanism of a casing suspended from the driven shaft, arms operatively connecting the casing with a part of the machine frame, a worm fixed to the driven shaft, a shaft rotatably supported in the casing, a train of gears operatively connecting the worm with the casing shaft, whereby the driven shaft and drawing rolls are revolved and given a traversing motion, in the machine.

8. The combination with a spinning machine having a driving mechanism, a driven shaft with drawing rolls and operatively connected with the driving mechanism, of a drawing roll traversing mechanism suspended from the driven shaft and operatively connected with the driven shaft and means for operatively connecting the drawing roll traversing mechanism with a fixed part of the machine frame.

9. A drawing roll traversing mechanism for spinning machines comprising a casing constructed to be suspended from the driven drawing roll shaft of the machine, a drawing roll traversing mechanism in the casing and operatively connected with the driven

drawing roll shaft and means for operatively connecting the drawing roll traversing mechanism with a fixed part of the machine frame.

10. The combination with a spinning machine having a frame, a driving mechanism, a driven drawing roll shaft operatively connected with the driving mechanism, of a casing operatively connected with the driven drawing roll shaft, a transverse shaft rotatably supported in bearings in the casing, cranks on the transverse shaft, a worm fixed to the driven drawing roll shaft, a gear having an even number of teeth fixed to the transverse shaft, a gear having an odd number of teeth and a hub rotatably supported on the transverse shaft, a worm gear meshing with the worm and having a hub rotatably supported on the hub of the odd number of teeth gear, a stud on the worm gear, a pinion on the stud straddling and meshing with both the even and odd teeth gears, arms operatively connecting the cranks on the transverse shaft with a part of the machine frame, back rolls engaging the driven drawing rolls and means for operatively connecting the back rolls with the casing of the drawing roll traversing mechanism, for the purpose as described.

In testimony whereof, I have signed my name to this specification.

SIGURD H. HELLAND.
